UNITED STATES PATENT OFFICE.

MOSES MITTELDORFER MARCUSE, OF FAR ROCKAWAY, NEW YORK, ASSIGNOR TO WEST DISINFECTING CO., OF NEW YORK, N. Y., A CORPORATION OF NEW YORK.

SANITARY MOUTHPIECE FOR TELEPHONES.

1,017,680.

specification of Letters Patent.

Patented Feb. 20, 1912.

Application filed January 25, 1911. Serial No. 604,655.

To all whom it may concern:

Be it known that I, MOSES M. MARCUSE, a citizen of the United States, residing at Far Rockaway, county of Queens, State of New York, have invented certain new and useful Improvements in Sanitary Mouth-pieces for Telephones, of which the following is a specification.

This invention relates to mouth pieces, 10 and particularly to the mouth piece of a telephone or like transmitter, into which the user directs his voice in carrying on a conversation at a distance.

The dangers of contagion from the use of 5 telephones used by more than one person are so great as to constitute a menace to public health. Not only is this true of the public or semi-public telephones, but also of the private instrument, as it has been found 20 that the collection of atmospheric dust in the telephone mouth piece is a source of infection on account of the inhalation of that dust, with the accompanying germs, in every use of the instrument. It is, therefore, 25 of the utmost importance that means be provided for protecting the user of the telephone so that it will not endanger the health of the public. Various attempts have been made to provide a mouth piece 30 which should be sanitary and capable of maintaining itself in a sterile condition. The nature of the instrument and its usage, however, are such as to impose many serious limitations upon the problem and to 35 render it a matter of extreme difficulty to devise a means sufficiently simple and yet effective.

To the end of producing a mouth piece as above described, I have devised my present 40 invention, which I will more fully describe in the specification which follows. As illustrative of my invention I shall show and describe a form of mouth piece which I have found well adapted to practical use 45 and capable of protection and service under actual practical conditions of telephone usage.

In this application I shall treat of my invention in the terms of an electric telephone 50 mouth piece, although it will be understood that I do not intend to limit myself by such language to this particular type of instrument, as a mouth piece is obviously capable of other usages, such as speaking tubes and 55 the like.

In the drawings which form a part of the specification I have shown the form referred to in the specification, like reference numerals being employed throughout both to indicate corresponding parts. 60

In the drawings:—Figure 1 is a view of a telephone transmitter equipped with my mouth piece, Fig. 2 is an enlarged sectional view of a mouth piece with cover closed, and Fig. 3 is a front view of the 65 same with cover open, exposing the outer diaphragm.

The usual casing 1 is fitted with a bell shaped mouth piece 2. Over the outer end of the mouth piece is located a protective 70 diaphragm 3 which is preferably perforated, as at 4, for the more ready transmission of the sound waves. To the diaphragm 3 is pivoted a shutter 5 having a central cup or chamber 6 in which is located 75 an absorptive pad 7 of felt or other material. The pad 7 is preferably held in place by a fastener 8 and is kept saturated with some suitable disinfecting, deodorizing or germicidal solution. 80

The shutter 5 swings laterally on its pivot 9 to expose the protective diaphragm 3, at the same time wiping across its surface to leave a moist film of the solution. The mouth piece is, therefore, when not in use, 85 covered by the shutter 5 and, when in use, presents to the user a surface free from dust and freshly wiped by a sterilizing pad which not only leaves it cleansed of any dirt or germs but deodorized, no matter 90 how unsanitary the circumstances of its last use.

Various modifications may obviously be made in the form and arrangement of the shutter and protective diaphragm and in 95 the construction and arrangement of the parts, all without departing from the spirit of my invention if within the limits of the appended claims.

What I, therefore, claim and desire to secure by Letters Patent is:—

1. In combination with the mouth piece of a telephone transmitter an auxiliary diaphragm mounted thereon, means for securing said diaphragm to said mouth piece, a 105 laterally movable shutter pivoted to said diaphragm and having a recess on the inner face thereof, a pad of absorptive material in said recess and adapted to contain a disinfectant to wipe across said dia- 110

phragm in the lateral movement of said shutter.

2. An auxiliary diaphragm for the mouth piece of a telephone transmitter comprising a disk, means on the margin of said disk for mounting said diaphragm upon a telephone mouth piece, a laterally movable shutter pivoted to said diaphragm and having a central cupped portion there-
10 in, an opening on its inner face and an ab-

sorptive pad in said shutter cup for holding a disinfectant to wipe said diaphragm, in the lateral movement of said shutter.

In testimony whereof, I affix my signature in presence of two witnesses.

MOSES MITTELDORFER MARCUSE.
